(57) **CLAIM**

The ornamental design for a pintle lock, as shown and described.

DESCRIPTION

FIG. 1 is a perspective view of a pintle lock, showing the new design;

FIG. 2 is a second perspective view thereof;

FIG. 3 is an exploded view of the pintle lock of FIG. 1 in use with a hitch;

FIG. 4 is a right-side elevation view of the pintle lock of FIG. 1;

FIG. 5 is a left-side elevation view thereof;

FIG. 6 is a front elevation view thereof;

FIG. 7 is a back elevation thereof;

FIG. 8 is a top plan view thereof;

FIG. 9 is a bottom plan view thereof; and

FIG. 10 is a cross-sectional view taken along line 10-10 of FIG. 9 thereof; and,

FIG. 11 is a side view of the pintle lock in use with a hitch. The broken lines in the figures show portions of the pintle lock and its environment and form no part of the claimed design.
